PHONOGRAPH PICKUP DEVICE

Lloyd J. Bobb, Glenside, Pa., assignor to Philco Radio and Television Corporation, Philadelphia, Pa., a corporation of Delaware

Application March 31, 1944, Serial No. 528,905

16 Claims. (Cl. 179—100.41)

This invention relates to phonograph pick-ups of the moving coil type intended for use with lateral-cut recordings.

To avoid the alternative of translating lateral oscillations of the pick-up stylus into axially directed oscillations of the moving coil and, at the same time, to ensure that the moving coil will cut enough magnetic flux lines to effect a satisfactory voltage output per turn, it is expedient that the moving coil be of rather considerable diameter; and in order to ensure transmission of mechanical oscillations of all desired frequencies from the stylus to the moving coil without inordinate loss or distortion it is necessary to employ a rigid, low-mass coil-supporting structure for mechanically coupling the coil with the stylus. But such a structure, if vibrated axially of the coil, will, unavoidably, displace a considerable volume of air and thus produce an objectionable amount of so-called "needle-talk"—which is noise propagated directly from the pick-up.

Although a lateral-cut recording is not intentionally designed to impart lengthwise vibratory motion to the pick-up stylus, it does so nevertheless, by virtue of what is called "pinch-effect"—which is a phenomenon resulting primarily from variations in the width of the record groove brought about as a consequence of the fact that the recording stylus cuts a groove of less depthwise angularity during its excursions laterally of the groove than it does when not moving laterally of the groove; and secondarily as a consequence of the fact that the reproducing stylus rests on the side-walls of the groove rather than on the bottom. In effect, the groove may be considered as having a "hill and dale" noise-producing component in addition to its intentionally-produced lateral undulations.

Lengthwise vibratory movements of a pick-up stylus caused by "pinch-effect" cannot be avoided by any correction in the design of the pick-up, but the present invention provides a pick-up construction which largely or completely obviates the otherwise resultant needle-talk; and such is one of its major objects.

According to the preferred mode of putting this invention into practice the moving coil is carried by a cup-like support comprising a generally cone-shaped member made of thin sheet metal, such as aluminum, and suspended for rotational oscillation on resilient pivots. The coil is wound on the base portion of the support and is situated in the magnetic field; and the actuating stylus extends axially through the apex of said coil-support to the exterior thereof and is anchored at its interior

end to a resilient stationary member, preferably a soft rubber block, which permits the stylus to vibrate both laterally and axially with considerable freedom, while at the same time affording essential mechanical damping. By providing a stylus support which allows the stylus freely to oscillate axially in response to "pinch-effect" conditions, record groove abrasion is substantially alleviated, as explained more fully in my co-pending application, Serial No. 502,003, filed September 11, 1943, now Patent No. 2,379,782, dated July 3, 1945; but, as previously indicated, oscillation of the coil-support axially of the stylus is objectionable because of the resultant needle-talk, and is a thing which inevitably would occur if the coil-support were fixedly secured to the stylus.

The solution of the problem thus presented consists, fundamentally, according to this invention, in the provision of a close sliding fit between the stylus and an aperture in the apex of the coil-support through which the stylus extends—which close sliding fit allows the stylus to vibrate lengthwise, substantially without any like movement being imparted to the coil-support, while at the same time affording good mechanical coupling between the stylus and coil-support as respects lateral vibration of the stylus.

If the fit of the stylus in the aforementioned aperture is such as to preclude lateral lost motion between stylus and coil-support while at the same time leaving the stylus free to vibrate lengthwise without transmitting such vibrations to the coil-support, a simple circular aperture will answer the purpose. But I have found it to be quite difficult with a circular aperture to limit lateral lost motion to such magnitude as would not result in objectionable attenuation of the higher audible frequencies while yet making certain that frictional coupling between stylus and coil-support would not give rise to inordinate vibration of the coil-support lengthwise of the stylus—which, as previously explained, results in needle-talk.

While endeavoring to meet that situation in a practical way, I discovered at length, after considerable experimentation, that by making the aperture of triangular or similar configuration and of suitable angularity and appropriate orientation with respect to the locus of the record groove, as explained hereinafter, it is possible to achieve a permanent close running fit which nullifies lateral lost motion while ensuring continued free longitudinal movement of the stylus without undue frictional drag. This feature of my invention results in suppression of needle-talk to a gratifying degree without introducing any per-

ceptible loss of fidelity while, at the same time, avoiding a large part of the record abrasion which would result from "pinch-effect" if the stylus were not so supported as to be quite yieldable lengthwise.

Due to high frequency background noise which is inherent in certain commercial records, usually as a result of granular structure of the record material, it often is preferable in playing such records to cut off all frequencies above some determined level such, for example, as five or six kilocycles. On the other hand, certain high quality records are not comparably afflicted with objectionable background noise and, in order to realize results which are most pleasing to the musically-trained ear, it is necessary, when playing such records, to employ a pick-up, amplifier and loud-speaker combination capable of reproducing faithfully all the high frequencies up to a level greatly in excess of six kilocycles, in addition to faithfully reproducing the middle register and the desirable bass frequencies.

I have discovered, as another aspect of this invention, that if the stylus is only lightly gripped at its upper end by the rubber member in which it is anchored it will go into rotational vibration about a center at or near the point where it contacts the coil-support, when actuated at and above some critical frequency and will thereupon fail to transmit efficiently to the coil-support all frequencies above said critical frequency. This means that the stylus will function as a low-pass mechanical filter or cut-off device if it is only lightly gripped at its upper end by the soft rubber in which it is embedded. Tightening the grip of the rubber on the stylus raises the frequency at which cut-off occurs. Thus, by squeezing the rubber around the stylus or by selecting a less resilient rubber compound, or both, the cut-off frequency can be raised to any desired extent. Hence, if it is purposed to provide a pick-up which is most satisfactory for playing commercial records afflicted with background noise, the stylus-supporting rubber member would be arranged to grip the stylus rather lightly and thus establish a cut-off point low enough to exclude most of the noise, but without too badly detracting from the tone quality. Conversely, if it is desired to provide a pick-up capable of faithfully reproducing frequencies up to a relatively high level, the rubber member would be arranged to grip the stylus more tightly.

Observance of the above-described phenomenon and recognition of the desirability of being able to play records of various qualities, each to the best possible advantage, has prompted me to conceive of means whereby the gripping action of the rubber on the stylus can quickly and easily be adjusted so as to raise and lower, at will, the cut-off level. What I consider to be the most convenient, operationally, and at the same time one of the most easily produced instrumentalities for carrying this idea into effect is a device in the nature of a collet chuck which serves as a holder for the rubber member and grips the same with a tenacity which is variable in response to rotation of an adjusting nut.

From the foregoing it may rightly be concluded that a second object of this invention is to provide a pick-up construction which can be adapted to cut off at any desired frequency level whereby to facilitate suppression of background noise; and that a third object is to devise means through which the cut-off level can be raised and lowered at will, so that the pick-up can be ad-

justed, as occasion demands, to give the most satisfactory reproduction which the quality of the record being played will permit.

A practical embodiment of the invention will 5 now be described with reference to the accompanying drawing, wherein:

Fig. 1 is a longitudinal sectional view, on a greatly enlarged scale, of a moving-coil pick-up incorporating the invention;

Fig. 2 is a view looking upwardly from below Fig. 1; and

Fig. 3 is a fragmentary sectional view taken along the line 3—3 of Fig. 1.

It is to be borne in mind that all three views are greatly magnified and that the pick-up device illustrated is in reality very small—the diameter of the moving coil being of the order of three-eighths inch while other dimensions are generally proportional.

Usually the field structure employed includes a permanent magnet together with suitable pole-pieces and other components; but the invention here under consideration does not entail any departure from prior practice as respects field structure design and for that reason I have indicated only such fragments of the field structure as are immediately adjacent the elements with which the invention has especially to do.

The field pole-pieces are indicated in Fig. 2 by reference numerals 1 and 2 respectively; and a core member 3 of magnetic material constitutes a passive part of the field structure and is situated midway between the pole-piece faces. Said core member provides a low reluctance path for the magnetic lines of force while at the same time serving as a support for elements presently to be described. It will be observed that core member 3 is circular in form, as viewed in Fig. 2, and that its upper end portion is of reduced diameter (see Fig. 1) and is pressed into a part 4 which supports the core member in fixed relation to the aforementioned pole-pieces.

Between each pole face and core member 3 is a narrow magnetic gap in which is disposed the moving coil 5. Said coil consists of a number of turns of fine copper or aluminum wire wound on the cylindrical and tubular base portion 6a of a cup-like thin metal coil-support 6, which preferably is cone-shaped below the cylindrical base portion and somewhat truncated at the apex portion 6b, as clearly illustrated in Fig. 1.

Coil-support 6 should be of low mass yet adequately rigid to transmit with minimum loss even the highest desirable frequencies from the stylus to the moving coil. Preferably it is formed from thin sheet aluminum, and to further reduce its mass without undue loss of rigidity it may be perforated with small holes as depicted in Fig. 2.

The pick-up is designed for use only with lateral-cut recordings and, accordingly, is pivotally supported to rotate about an axis corresponding approximately to line 7 in Figs. 1 and 2. The plane of oscillation of the coil support and coil is indicated by arrows 8 and 9 in Fig. 2, and said plane is radial to the arc of the record groove represented in Fig. 2 by line 10. The direction of rotation of the record is indicated by arrow heads on line 10.

The means employed for pivotally mounting the coil-support is not of the essence of the present invention, but it is advantageous and economical to make use of a pair of elongated rectangular soft rubber blocks 11 and 12 which are seated in diametrically opposite slots formed in core member 3, and which rubber blocks bear

against opposite interior surface areas of the coil support, as clearly shown in Fig. 1. These soft rubber pivotal supports constitute subject matter of my above-mentioned co-pending application, and their use is particularly desirable here because they make it easy to withdraw the moving coil and coil-support from the pick-up in event it becomes necessary to make a replacement.

The pin or rod 13 and the pointed sapphire or needle-point 14 embedded in its lower end are here denominated, collectively, as the stylus. The sapphire or needle-point is, of course, intended to engage the record groove and the stylus is oscillated laterally by the undulations of said groove in the plane indicated by arrows 8 and 9. The upper end of the stylus is embedded in a bushing-like member 15 of resilient material such as soft rubber, which normally functions as a pivotal center or fulcrum about which the stylus oscillates when actuated by the record groove undulations. Member 15 also allows the stylus to move freely lengthwise of itself, to a limited extent, relatively to the other parts of the pick-up, and it further functions as a damping means for preventing free vibration of the stylus, besides operating as a cushion to absorb the force of the blow in event the pick-up is accidentally dropped on the record.

It is essential to good operation of the pick-up that lateral oscillations of the stylus which are imparted thereto by the lateral record undulations be transmitted faithfully and with substantially full magnitude to coil-support 6 and thence to moving coil 5, whereby to cause oscillatory rotation of coil 5 about axis 7 in accurate conformity with the record groove undulations corresponding to the recorded sound. But it is greatly to be desired that lengthwise vibration of the stylus be not transmitted to coil-support 6 because such vibration of the coil-support would give rise to what has hereinbefore been described as "needle-talk"; and since the surface area of the coil-support is necessarily considerable the audible disturbance would be quite pronounced if such transmission were not prevented or at least greatly restricted. Substantial avoidance of needle-talk is here achieved by providing an aperture in the apex of the coil-support which affords a close running fit for the stylus—thus permitting the stylus to oscillate lengthwise independently of and relatively to the coil-support while eliminating or substantially restricting lateral lost motion between stylus and coil-support. This desirable result can be accomplished with a simple aperture of circular or other configuration gauged to slidably fit the stylus; but it is difficult to achieve and maintain, with a circular aperture, a close sliding fit and at the same time prevent the coil-support sticking to the stylus and being resultantly vibrated with the stylus in the axial direction.

As a result of considerable thought and experimentation I have found a wholly practical solution of the aforementioned difficulty, and this consists in the provision of an apex aperture 16 (see especially Fig. 2) so formed as to present to the stylus a V-slot having an acute angle α so oriented with respect to the record groove that the traction of the record pulls the stylus forwardly into said slot. This ensures that the stylus will always bear against the two sides of the V-slot so that there can be no lateral lost motion between stylus and coil-support as the stylus oscillates laterally in response to the record groove undulations; but it is necessary that the

said angle α be neither too small nor too large. If said angle is too small the radial pressure between the stylus and contacting surfaces of the aperture may be great enough to cause the coil-support to follow lengthwise oscillations of the stylus as a consequence of frictional drag; and if said angle is too large there is apt to result an excess of lateral lost motion. I have found experimentally that an angle α of about thirty degrees is generally satisfactory, although that value is not to be regarded as highly critical and (because of differences in frictional constants as between various interengaged materials) it may not even be optimum in all cases.

In order to reduce wear and minimize friction, I prefer to deform the apex of the coil-support into a well or recess, as shown in Fig. 1, for the reception of a small horn fiber disk 17, which is cemented in place and apertured as shown. The aperture 18 in the sheet metal is large enough to clear the stylus so that the latter bears only on the fiber surface. Fiber happens to be a good bearing material for this purpose, but any other suitable material could be substituted.

I have observed that if the material constituting the bushing-like member 15 is quite yieldable and is compressed only lightly around the upper end of the stylus, the latter will oscillate about its upper end as a fulcrum throughout a frequency band comprising the lower and middle register and frequencies up to say four or five kilocycles. At some frequency of the order of four or five kilocycles, or thereabout, the center of vibration of the stylus will abruptly shift from the upper end thereof to the region immediately adjacent disk 17; and this, of course, means that the stylus is no longer highly effective as a medium for transmitting the record undulations to the coil-support and that, consequently, the frequencies above the point where the above-mentioned shift occurs are largely or completely suppressed. By using a less yieldable material for member 15 or by increasing the compressive force thereon, or both, the frequency at which suppression or cut-off occurs may be raised. It is thus possible to vary the cut-off level by several kilocycles—which renders it practicable to specifically design the pick-up for playing to best advantage either low grade or high grade records or to establish the cut-off point at a level which represents a compromise between the two.

So far nothing has been said in this detailed description concerning the provision for varying at will the cut-off point; and that omission is deliberate in that I wish to emphasize that the feature under discussion is not basically dependent upon the inclusion of adjusting means which permit the user to alter the point of cut-off from time to time as he may see fit.

It may not be feasible to market indiscriminately a pick-up which is capable of being incorrectly adjusted with respect to the particular record to be played, and for that reason sales to the general public of pick-ups constructed in accordance with this invention may be largely confined to such as are fixedly adjusted at the outset to cut off at such a level as will produce the best results with ordinary records. But as concerns the class of trade capable of appreciating the necessity of making appropriate adjustments in harmony with the quality of the record in hand, it is practicable to supply pick-ups having the feature of adjustability depicted in Figs. 1 and 3 and presently to be described.

Instead of simply inserting rubber bushing 15

into a recess drilled in core member 3 and fixedly determining at the outset the tenacity with which said bushing grips the stylus, the bushing may be mounted in a collet 19 which is split at three or more points 20, as shown in Fig. 3, and provided with an arbor 21 threaded at its upper end and engaged by a knurled adjusting nut 22. The collet bears at 23 against a tapered internal surface in recess 24 which causes the collet to contract and increase its grip upon bushing 15 when nut 22 is turned in the direction which will cause an upward movement of arbor 21. Opposite rotation of nut 22 will cause the compressive force on bushing 15 to be diminished. Thus, the user is enabled to adjust the pick-up to best advantage for any record which he may be about to play. It will be apparent that the feature just described constitutes a mechanical low-pass wave filter whereof the point of cut-off may be adjustable by the user or, alternatively, may be determined and fixed at the factory.

Since the stylus is only frictionally secured to bushing 15 it can, whenever necessary, easily be withdrawn for replacement; and this does not necessitate removal of the coil-support.

I claim:

1. The combination in a phonograph pick-up for playing lateral-cut recordings, of a moving coil pivotally mounted for rotary oscillation in a magnetic field about an axis of rotation extending transversely of the coil, an elongate stylus adapted at one end to engage a record groove, a resilient anchorage for the other end of said stylus, which anchorage is operative as a fulcrum about which said stylus is rotatable in response to actuation by the record groove undulations, said anchorage being yieldable to permit lengthwise oscillatory movement of said stylus to a limited extent, and structure intercoupling said coil with said stylus for translating lateral oscillations of the stylus into corresponding rotational oscillations of the coil about said axis, said stylus being movable lengthwise substantially without imparting motion to said structure.

2. The combination in a phonograph pick-up for playing lateral-cut recordings, of a pivotally mounted coil-support, a moving coil wound on said support and rotatable therewith, and a stylus for actuating said coil-support in response to record groove lateral undulations, said stylus being so coupled to said coil-support that lateral oscillations of the stylus are transmitted efficiently through the coil-support to said moving coil in a manner effective to oscillate said coil in harmony with the lateral record groove undulations, said stylus being movable lengthwise independently of said coil-support and therefore yieldable to pinch-effect without actuating said coil-support.

3. The combination in a phonograph pick-up for playing lateral-cut recordings, of a cup-like coil-support having a base portion and an apex portion axially spaced from said base portion, a moving coil wound on said base portion, said coil-support being pivotally mounted and having an axis of rotational oscillation extending diametrically of said coil and through said base portion, the apex portion of said coil-support having an aperture, a stylus extending from the interior of said coil-support through said aperture to the exterior of said support and adapted to engage a record groove at its exterior end, the other end of said stylus being resiliently anchored so that it is relatively free to move length-

wise to a limited extent, said stylus having a sliding fit in said aperture.

4. The combination in a phonograph pick-up for playing lateral-cut recordings, of a cup-like coil-support having a main axis, said coil-support including a base portion concentric with said main axis and an apex portion concentric with said main axis and spaced from said base portion along said main axis, said coil-support having an axis of rotational oscillation extending through said base portion perpendicularly to said main axis, a moving coil wound on said base portion, an elongate stylus having a longitudinal axis coincident with said main axis, said stylus extending through and slidably fitting an aperture in said apex portion, one end of said stylus being adapted to engage a record groove, and resilient means for anchoring the other end of said stylus, said resilient means being operative as a fulcrum about which said stylus oscillates when actuated by a lateral-cut record groove, said resilient means being yieldable to permit said stylus freely to vibrate lengthwise to a limited extent.

5. The combination in a phonograph pick-up for playing lateral-cut recordings, of a coil-support having a main axis, a moving coil wound on said coil-support concentrically with said main axis, said coil-support having an aperture through which said main axis extends, the configuration of said aperture, as viewed when looking endwise at said axis, including a V-slot, an elongate stylus having its longitudinal axis approximately coincident with said main axis and extending through said aperture, one end of said stylus being exterior of said coil-support and adapted to engage a record groove, and means forming a resilient anchorage for the other end of said stylus, said V-slot being so oriented that the stylus is forced forwardly into it by the traction of the moving record groove on the stylus, said V-slot being effective to preclude lost motion between said stylus and coil support with respect to lateral oscillatory motion imparted to the stylus by the lateral record groove undulations, said stylus being freely slidably lengthwise through said aperture, said coil-support, together with said coil, being mounted for rotational oscillation about an axis extending diametrically of said coil.

6. The combination in a phonograph pick-up for playing lateral-cut recordings, of a moving coil pivotally mounted for rotary oscillation in a magnetic field about an axis of rotation extending transversely of the coil, an elongate stylus adapted at one end to engage a record groove, a resilient anchorage for the other end of said stylus, which anchorage is operative as a fulcrum about which said stylus is rotatable in response to actuation by the record groove lateral undulations, said anchorage being yieldable to permit lengthwise oscillatory movement of said stylus to a limited extent, and structure for translating lateral oscillations of the stylus into corresponding rotational oscillations of the coil, said structure having an aperture forming a bearing in which said stylus is a close sliding fit and which constitutes the medium coupling the stylus to the structure for effectuating the aforementioned translation.

7. The combination in a phonograph pick-up for playing lateral-cut recordings, of a moving coil pivotally mounted for rotary oscillation in a magnetic field about an axis of rotation extending transversely of the coil, an elongated stylus

adapted at one end to engage a record groove, a resilient anchorage for the other end of said stylus, which anchorage is operative as a fulcrum about which said stylus is rotatable in response to actuation by the record groove lateral undulations, said anchorage being yieldable to permit lengthwise oscillatory movement of said stylus to a limited extent, and structure for translating lateral oscillations of the stylus into corresponding rotational oscillations of the coil, said structure having an aperture forming a bearing in which said stylus is a close sliding fit and which constitutes the medium coupling the stylus to the structure for effectuating the aforementioned translation, the configuration of said aperture, as viewed when looking from one end of said stylus, being non-circular and including a V-slot oriented to receive said stylus, the latter being movable forwardly into the V-slot by the traction of the moving record.

8. The combination in a phonograph pick-up for playing lateral-cut recordings, of a cup-like coil-support having a main axis, said coil-support having a tubular base portion concentric with said main axis and an apex portion spaced from said base portion lengthwise of said main axis, said coil-support including a conical portion interconnecting said base portion and apex portion, a magnetic core member disposed within said base portion, pivot means suspending said coil-support from said core member and arranged to permit rotary oscillation of said coil-support about an axis extending transversely of said main axis and through said base portion, a moving coil wound on said base portion, a rubber-like member carried by said core member within said coil-support, and an elongate stylus having its longitudinal axis coincident with said main axis, one end of said stylus being anchored in said rubber-like member, said stylus extending through an aperture in said apex portion to the exterior of said coil-support and adapted at its exterior end to engage a record groove, said stylus being closely fitted to said aperture to avoid lateral lost motion between the stylus and the coil-support, said stylus being freely slidable lengthwise through said aperture.

9. The combination in a phonograph pick-up for playing lateral-cut recordings, of a cylindrical magnetic core member having a main axis, a cup-like coil-support having a base portion encircling said core member and concentric with said main axis, resilient means pivotally connecting said coil-support to said core member and permitting said coil-support to oscillate rotationally about an axis extending diametrically through said base portion and perpendicularly to said main axis, said coil-support having an apex portion concentric with said main axis and spaced from said base portion, a non-metallic member carried by said coil-support at said apex portion and having an aperture, the configuration of said aperture, as viewed when looking endwise at said main axis, being non-circular and including a V-slot portion, a resilient rubber-like insert carried by said core member, and an elongate stylus having its longitudinal axis substantially coincident with said main axis, one end of said stylus being anchored in said insert, said stylus extending through said aperture and adapted at its other end to engage a record groove, said V-slot portion being so oriented that the traction of the record forces said stylus into said V-slot portion, the angularity of said V-slot portion being so chosen that said

stylus is free to oscillate longitudinally independently of said coil-support while at the same time lateral lost motion between the stylus and coil-support is obviated.

10. The combination in a phonograph pick-up for playing lateral-cut recordings, of an elongate stylus, a resilient rubber-like member embracing one end of said stylus and constituting an anchorage therefor, adjustable means for variably compressing said rubber-like member for altering its grip on said stylus, a moving coil, and structure for transmitting lateral oscillatory movements of said stylus to said moving coil, said stylus being movable lengthwise independently of said structure.

11. The combination in a phonograph pick-up for playing lateral-cut recordings, of an elongate stylus, a resilient rubber-like member embracing one end of said stylus and constituting an anchorage therefor, a contractible-expansive collet embracing said rubber-like member, manually operable means for adjusting said collet for varying its grip on said rubber-like member, a moving coil, and structure for transmitting lateral oscillatory movements of said stylus to said moving coil, said stylus being movable lengthwise independently of said structure.

12. The combination in a phonograph pick-up for playing lateral-cut recordings, of a core member having a main axis, a cup-like coil-support concentric with said main axis and having a base portion encircling said core member, said coil-support having an apex portion concentric with said main axis and spaced from said base portion along said main axis, said core member having an axial bore terminating in a recess at the end within said coil-support, a collet chuck seated in said recess and having an arbor passing through said bore, means for moving said arbor lengthwise for actuating said chuck, a resilient rubber-like member gripped by said chuck, and an elongate stylus embedded at one end in said rubber-like member and extending through an aperture in said apex to the exterior of said coil-support, the other end of said stylus being adapted to engage a record groove, said stylus slidably fitting said aperture and freely movable therein lengthwise, said coil-support being pivoted for rotary oscillation about an axis perpendicular to said main axis and remote from said apex.

13. The combination in a phonograph pick-up for playing lateral-cut recordings, of a coil-support having a main axis, said coil-support including a base portion and an apex portion spaced from said base portion along said main axis, a moving coil wound on said base portion concentrically with said main axis, said coil-support being pivotally mounted and having an axis of rotational oscillation extending diametrically of said coil and perpendicularly of said main axis, an elongate stylus having a longitudinal axis substantially coincident with said main axis, said stylus extending through said apex portion and drivingly coupled thereto to said coil-support, the exterior end of said stylus being adapted to engage a record groove, and a rubber-like member forming a pivotal anchorage for the other end of said stylus and in gripping engagement therewith.

14. The combination in a phonograph pick-up for playing lateral-cut recordings, of a coil-support having a main axis, said coil-support including a base portion and an apex portion spaced from said base portion along said main axis, a moving coil wound on said base portion concentrically with said main axis, said coil-support being pivotally mounted and having an axis of rotational oscillation extending diametrically of said coil and perpendicularly of said main axis, an elongate stylus having a longitudinal axis substantially coincident with said main axis, said stylus extending through said apex portion and drivingly coupled thereto to said coil-support, the exterior end of said stylus being adapted to engage a record groove, and a rubber-like member forming a pivotal anchorage for the other end of said stylus and in gripping engagement therewith.

trically with said main axis, said coil-support being pivotally mounted and having an axis of rotational oscillation extending diametrically of said coil and perpendicularly of said main axis, an elongate stylus having a longitudinal axis substantially coincident with said main axis, said stylus extending through said apex portion and drivingly coupled thereto said coil-support, the exterior end of said stylus being adapted to engage a record groove, a rubber-like member forming a pivotal anchorage for the other end of said stylus, and adjustable means for variably gripping said rubber-like member for altering its grip on said stylus.

15. The combination in a phonograph pick-up for playing lateral-cut recordings, of an elongate stylus, a resilient rubber-like member embracing

one end of said stylus and constituting an anchorage therefor, a contractible-expansible collet embracing said rubber-like member, a moving coil, and structure for transmitting lateral oscillatory movements of said stylus to said moving coil, said structure being connected to said stylus at a point remote from said anchorage.

16. In a moving-coil type phonograph pick-up for playing lateral-cut recordings, a coil arranged for oscillatory movement, a stylus adapted to engage a record, means supporting said stylus for both longitudinal and lateral movements, and means for effecting oscillatory movement of said coil in response to lateral movement of the stylus while permitting longitudinal movement of the stylus substantially independently of said coil.

LLOYD J. BOBB.
